UNITED STATES PATENT OFFICE.

THEODORE J. RADKE, OF CHICAGO, ILLINOIS.

WATER-CONTROLLED GAS-DISTRIBUTING VALVE.

1,036,557.

Specification of Letters Patent. Patented Feb. 10, 1914.

Application filed November 6, 1911. Serial No. 688,768.

To all whom it may concern:

Be it known that I, THEODORE J. RADKE, a citizen of the United States, and a resident of Chicago, in the county of Cook and State of Illinois, have invented certain new and useful Improvements in Water-Controlled Gas-Distributing Valves; and I do hereby declare that the following is a full, clear, and exact description thereof, reference being had to the accompanying drawings, and to the characters of reference marked thereon, which form a part of this specification.

This invention relates to a novel gas distributing valve adapted to be arranged between the gas supply pipes and meters belonging to a number of consumers and the burner of a single water heater, which heater is used in common by said consumers, the arrangement being such that each consumer, when drawing water from the heater, will automatically operate the distributing valve in such a way as to open his own gas supply pipe only to the heater burner, and at the same time close the other pipe or pipes, so as to thereby use only his own gas to heat the water which he draws from the heater; and the invention relates also to a system embracing a plurality of metered gas service pipes, a plurality of water draw-off pipes and a heater from which hot water is withdrawn, with means for controlling the gas for supplying the burner of the heater, so arranged that the gas supply pipe of a given consumer is opened to supply gas to the burner when the water service pipe of that consumer is open to withdraw water from the heater, the other gas service pipes being at this time closed. The said gas distributing valve is adapted for use with quick or instantaneous water heaters of that kind wherein water from a source under pressure is forced into and through a heating coil, arranged over the burner, so that when water is drawn from the outlet end of the coil it is quickly heated as it passes through the coil. The heater burner may be supplied with gas through a conduit that is provided with an automatic valve which is controlled to admit water to the coil when hot water is being drawn therefrom, the gas valve of the burner supply conduit being open when water is passing through the heater, and closed at other times. In certain constructions of burners gas may be continuously supplied from the latter conduit to the pilot burner in such a way that the extinguishment of the

pilot burner flame has the effect to cut off the supply of gas, not only to the pilot burner, but the main burner of the heater. A heater of the latter kind is shown in my prior U. S. Letters Patent No. 972,717 dated the 11th day of October, 1910. I have herein shown a convenient construction of my novel gas distributing valve adapted to a heater such as shown in my Letters Patent, and have shown another form adapted to heaters which do not employ the pilot burner controlled mechanism.

The invention consists in the matters hereinafter set forth and more particularly pointed out in the appended claims.

In the drawings;—Figure 1 is a side elevation of a gas distributing valve embodying my invention. Fig. 2 is a longitudinal vertical section thereof. Fig. 3 is a similar section of a modified form of valve. Fig. 4 illustrates, diagrammatically, the manner of connecting my device between a heater burner and a plurality of metered gas supply pipes.

As shown in the drawings and referring particularly to Fig. 4, 10 designates a heater, 11 a water supply pipe and 12 a gas supply pipe, the latter shown as having two service pipes 14, 15 equipped with meters 16, 17. 18 designates, as a whole, one form of my novel gas distributing valve (illustrated in detail in Figs. 1 and 2) which is located between the metered service pipes and the heater. 19 designates a pipe leading from the distributing valve 18 to the casing of the automatically controlled gas valve, diagrammatically indicated at 20 in Fig. 4. The water supply pipe enters the casing of an automatically controlled water valve, 95 diagrammatically indicated at 21 in Fig. 4, from which the cold water passes through the pipe 22 to the heater. The valves diagrammatically indicated at 20 and 21 may be like those shown in my aforesaid prior patent or may be otherwise constructed to effect the same general result, as set forth in said patent. The hot water passes from the heater through the pipe 23 to a water header in the distributing valve 18 and two distributing pipes 24, 25 lead from the water side of the valve to different points of water distribution.

Referring now to the specific form of device shown in Figs. 1 and 2, and which is shown as embodied in the system shown in Fig. 4, the same is made as follows: 30 design-

2
nates a hollow casting at the gas side of the device in which is formed a header 31 provided with a gas outlet nipple 31' for connection to the pipe 19. Said header 31 is common to and communicates, through valve controlled passages, with valve chambers 32, 33 that are provided with nipples 34, 35 which connect to the gas service pipes 14 and 15, respectively. At the water side of the distributing valve is arranged a hollow casting 38, generally similar to the casting 30, in which is formed a header 39 having a screw-threaded hot water inlet nipple 40 for connection to the hot water pipe 23. The header 39 is common to and communicates through the cylindrical passages 42, 43 with valve chambers 44, 45 provided with nipples 46, 47 for connection to the hot water distributing pipes 24 and 25. The casting 30 and 38 are connected by the frame members 50 which are connected at the median line of the device by the screw bolts 51, 51 which extend through lugs 52, 52 on the adjacent inner ends of said frame members. The arrangement of the frame in two parts and connected as shown facilitates the disassembly of the device, as will be obvious.

The valve chambers are arranged in opposite pairs, with each water valve chamber 30 axially opposed to a gas valve chamber. The flow of the gas from the gas valve chambers 32, 33 to the header 31 is herein shown as controlled by conical disk valves 55 which engage conical body seats 56, 56 surrounding the passage connecting the valve chambers with the header 31. The said disk valves 55 are mounted on endwise reciprocating stems 57, 57 arranged axially in the valve chambers and have guiding engagement at the outer ends in guide sockets 58 in the outer wall of the header 31. The inner ends of said stems extend through and guidingly engage plugs 60 screw-threaded in the inner ends of said valve chambers and 45 constitute the inner walls thereof. Familiar forms of stuffing box members 61, 61 surrounding the stems and screw-threaded to extensions of the plugs 60 provide gas tight joints about said stems.

50 The passage of the water from the header 39 on the water side of the valve device is controlled by the disks 63, 63 which are fixed to endwise reciprocating stems 64, 64 arranged axially in alignment with the stems 57, 57 and have guiding arrangement at their outer ends in sockets 65 formed in the outer wall of the header 39. The stems 64 extend through and guidingly engage plugs 66, 66 which have screw-threaded engagement with 60 the inner ends of the water valve chambers 44, 45 and constitute the inner end walls of said chambers. Stuffing boxes 67, 67 are arranged on the extended parts of the plugs 66 around said stems to form water tight joints between the wall and the stems.

The valve disks 55 are mounted to slide loosely on the stems 57 and are confined on said stems between inner and outer spiral springs 70, 71, the inner spring 70 being interposed between said disks and collars 72, 72 which latter are pinned or otherwise fixed to the stems 57. The outer springs are interposed between the disk valves and the outer wall of the header casting 30, the outer ends of said springs 71 surrounding the socket nipples 58, 58. Said outer springs 71 are made weaker than the inner springs 70 for a purpose hereinafter to be described.

The stems 57 and 64 of the opposing water and gas valve bear at their inner ends 80 against the outer ends of a lever 75 which is centrally pivoted to a pin 76 that is mounted in and extends between the members of a yoke 77 arranged transversely across the device between the pair of valves. As herein shown said yoke is made of cast metal and is connected to the frame members 50 by means of plates 78 attached to or cast in the yoke 77 and clamped at their outer ends between said frame members 50.

90 The operation of the device described is as follows: When no water is being drawn from the heater the lever 75 occupies its mid-position and both the disks 63 on the water side of the valve occupy the cylindrical passages 43 which connect the water header 39 with the water valve chambers. The disk valves 55 are held closely adjacent to, but not in actual contact with, conical body seats 56 so that at this time a small 100 volume of gas may pass from both the consumers' service pipes 14 and 15 through the valve device and the pipe 19 to supply the pilot burner of the heater. If water be drawn from one of the pipes 24 or 25 the 105 pressure will be reduced on the inner side of the valve disk 63 associated with the chamber with which the open pipe 24, 25 is connected, so that the superior pressure of water in the header 39 forces the said disk 110 inwardly to permit the water to flow past the same into the open draw-off pipe. When said disk is thus forced inwardly its stem acts, through the lever 75, to force the axially opposed gas disk valve tightly against 115 its seat, as shown in the lower side of Fig. 2, so as to thereby close the valve chamber 33 to the header 31. The pivotal movement of the lever 75 on its axis, caused by the axial movement of the stem 64, has the effect to 120 force the other water controlled disk 63 outwardly, as clearly shown in Fig. 2, and permits the axially opposed valve disk 55 to be moved away from its seat 56 under the action of the spring 71, as shown in the upper 125 right hand side of Fig. 2. It will be understood that when the valves are in their normal or balanced positions and no water is flowing from the heater, the springs 71 are placed under considerable pressure, while 130

the springs 70 may be placed under slight pressure. The force of the springs 71 therefore opens the gas valves when the latter are free to open. The said springs 70 are provided, in connection with the valve disks which are slidingly fitted on their stems, in order to insure that the disks 55 shall be firmly seated without necessitating great accuracy of movement of the parts, for should either of the disk valves reach its seat before the full movement of the parts have been accomplished, its associated spring 70 will permit such additional movement of its stem as may be required to complete the full movement of the parts.

It will be seen from the foregoing that the water and gas valves which are operative at a time when water is being drawn through one of the water draw-off pipes are located at diagonally opposed corners of the device, as best shown in Fig. 2; the upper gas valve being open and the lower water valve being open. When the water draw-off pipe is closed the pressure on the opposite sides of the disk 63 past which the water is flowing is equalized and the spring 71 associated with the closed gas valve will operate through the lever 75 to restore the gas valves to their normal positions and also to close the previously opened water valve. The operation of the other two diagonally disposed water and gas valves is, of course, the same as the pair of valves just described.

It will be noted that both the consumers' service pipes may be connected through the partially closed gas valve to contribute equally to the pilot burner, and that when water is being drawn from either of the pipes, the gas valve associated with that draw-off pipe will be opened and the other gas valve will be closed. Thus the supply of gas to heat the water to be drawn off will pass wholly through the meter of the consumer whose draw-off pipe is open.

The form of device shown in Figs. 1 and 2 is adapted to a heater supplying two consumers, although a device embodying the same general features of construction and operation may be arranged to control the gas supply for a plurality of heaters.

In Fig. 3 I have shown a modification which is adaptable for connection with any number of consumers' service pipes and an equal number of draw-off pipes. In said construction the gas and water headers 85, 86 the gas and water valve chambers 87, 88 and the disk valves 89, 90, respectively, are arranged in the same general manner as shown in Figs. 1 and 2, with each gas valve chamber arranged axially in line with a water valve chamber. The outlet 91 for the gas header and the inlet 92 for the water header open at the ends of said headers. In the latter construction the adjacent ends of axially alined stems 94, 95 of the water

and gas valves bear directly against each other, without the interposition of a lever or like motion transmitting device, as shown in Figs. 1 and 2, so that when either one of the water valves is open, its stem acts directly against the stem of an axially opposed gas valve to open the same, the other gas valves at this time remaining closed. The gas valves are closed by the springs 97 when the water pressure transmitted through the associated water valve is released, the spring 97 acting at the same time to close both the gas and water valves. In the construction shown in the said Fig. 3 the gas valves are normally tightly closed so that no gas is permitted to pass through the valve device to constantly supply a small volume of gas to the pilot burner. In a system which employs the device shown in Fig. 3, therefore, the supply for the pilot burner may be taken from the consumers' service pipes in any suitable or approved manner.

It will be noted that in both the constructions the multi-valved construction, comprising the coating water and gas valves, is a single unit, which is connected to the single burner of the heater and to the hot water end of the heater, each by a single gas and hot water pipe, respectively. This arrangement contributes to the compactness, economy and simplicity of the device, and brings the coating gas and water valves in an exceedingly practical relation for installation and operation.

I claim as my invention:—

1. A gas distributing valve device for supplying gas to the burner of a water heater which serves a plurality of consumers, comprising a plurality of gas valves, equal in number to that of the consumers served by the heater, an equal number of water valves appropriated one to each consumer, operative connections between said gas and water valves constructed, upon the opening of one of the water valves to open a gas valve appropriated to the consumer served by the open water valve and to permit the other gas valves to close, and means whereby all of the gas valves are maintained partially open when all the water valves are closed.

2. A water controlled gas distributing valve for the purpose set forth, comprising a frame provided at opposite sides with water and gas headers, provided, respectively with inlet and exit passages, and with water and gas valve chambers separately communicating with the headers through passages, valves in said passages, arranged with each water valve axially opposite to a gas valve, operative connections between the water and the gas valves, operative upon the opening of each water valve to open the operatively connected gas valve and to permit the other gas valve to close, and means

whereby the gas valves are slightly open when all the water valves are closed.

3. A water controlled gas distributing valve for the purpose set forth, comprising a frame provided at its opposite sides with axially alined water and gas valve chambers, and with water and gas headers provided, respectively, with inlet and exit openings, and communicating through passages with the water and gas valve chambers, valves to control said passages provided with valve stems arranged in axially alined pairs, and a lever pivoted to the frame with its ends between the axially alined stems of the valves.

4. A water controlled gas distributing valve for the purpose set forth, comprising a frame provided at opposing sides with water and gas headers and with water and gas valve chambers communicating with the headers through passages, valves in said passages, arranged with each gas valve axially opposite a water valve, operative connections between the water and gas valves which operate upon the opening of each water valve to open the operatively connected gas valve and to permit the closing of the other gas valve, the gas valves being movable on their stems, and each gas valve being held between two springs, one interposed between the valve and said frame and the other interposed between the valve and a shoulder on its stem.

5. A water controlled gas distributing valve for the purpose set forth, comprising a frame provided at opposing sides with water and gas headers and with water and gas valve chambers, communicating with the headers through passages, valves in said passages arranged with each water valve axially opposite a gas valve, operative connections between the water and the gas valves to open each gas valve upon the opening of its associated water valve, and to permit the other gas valves to close, the passages connecting the water valve chambers and the water header being made cylindric, and the water valves being cylindric and

movable into and out from cylindric passages.

6. The combination with the burner of a water heater, a plurality of consumers' gas pipes for furnishing gas to the burner and a plurality of draw-off pipes connected to the heater, of a gas distributing valve device between the service pipes and the burner, controlled by the withdrawal of water from said draw-off pipes, means to open each consumer's service pipe to the burner that is associated with the open draw-off pipe, while closing the service pipe of the other consumer, and means whereby the gas valves remain slightly open to furnish gas to a pilot burner when all the water valves are closed.

7. The combination with a water heater and its single burner, of a water controlled gas valve device comprising a frame or support hollowed at one side to provide a gas header and a plurality of gas inlet chambers severally connected to the header by ports, said gas header having a single outlet, the frame being hollowed on the other side to provide a hot water header and plurality of water outlet chambers severally connected to the water header by ports, said header having a single inlet opening, valves controlling the flow of gas from said gas inlet chambers to said header, other valves controlling the flow of water from said hot water header to said hot water outlet chambers, operative connections between each water valve and a companion gas valve to open the latter upon the opening of the water valve, a single pipe connecting the gas header outlet to said burner and a single pipe connecting said header to the said hot water header inlet.

In testimony, that I claim the foregoing as my invention I affix my signature in the presence of two witnesses, this 28th day of October, A. D. 1911.
